CLAIM

We claim the ornamental design for a toner cartridge, as shown.

DESCRIPTION

FIG. 1 is a front elevational view of a toner cartridge showing our new design;

FIG. 2 is a rear elevational view thereof;

FIG. 3 is a right-side elevational view thereof;

FIG. 4 is a left-side elevational view thereof;

FIG. 5 is a top plan view thereof;

FIG. 6 is a bottom plan view thereof;

FIG. 7 is a front perspective view thereof; and,

FIG. 8 is a rear perspective view thereof.

The broken lines in the drawings illustrate portions of the toner cartridge that form no part of the claimed design.
